PUMP

Benjamin F. Schmidt, Los Angeles, Calif.

Application September 28, 1931
Serial No. 565,427

16 Claims. (Cl. 103—204)

This invention relates to pumps and particularly pertains to said pump of the type including a piston reciprocable in a body of mercury or other protective liquid of greater density than a fluid to be pumped, and more especially appertains to improvements in pumps of the character set forth in my copending applications for United States Letters Patents, Serial Number 465,835, filed July 7, 1930, and Serial Number 10 498,943, filed November 29, 1930.

An object of the invention is to provide a pump of the reciprocal piston type in which the piston is so arranged as to be protected by a body of liquid, such as mercury, entrapped within the pump casing in such manner as to inhibit the passage of sand or other granular substances contained in the fluid being pumped, between the contiguous wearing surfaces of the piston and the walls of the pump, and whereby the discharge of sand or other granular solids associated with the fluids in the pump will be facilitated.

Another object is to provide a pump of the above character which is so formed as to maintain a protective liquid in and around a hollow or tubular pump piston in substantially predetermined proportions interiorly and exteriorly thereof, and whereby the possibility of loss of the protective liquid during operation of the pump will be obviated.

With the foregoing objects in view, together with such other objects and advantages as may subsequently appear, the invention resides in the parts and in the combination, construction and arrangement of parts hereinafter described and claimed and illustrated by way of example in the accompanying drawings, in which:

Figure 1 is a view in vertical section partly in elevation of a pump and with parts broken away, illustrating one embodiment of the invention, the pump piston being shown in its lowermost position;

Figure 2 is a diagrammatic view of the pump shown in Figure 1 as seen in section and elevation on a reduced scale for illustrating the mode of operation of the pump;

Figure 3 is a view similar to that of Figure 2, but showing the pump piston in an elevated position;

Figure 4 is a detail in cross section as seen on the line 4—4 of Figure 1;

Figure 5 is a detail in cross section as seen on the line 5—5 of Figure 1;

Figure 6 is a detail in cross section as seen on the line 6—6 of Figure 1;

Figure 7 is a detail in vertical section as seen on the line 7—7 of Figure 3;

Figure 8 is a detail in cross section taken on the line 8—8 of Figure 7;

Figure 9 is a detail in cross section taken on the line 9—9 of Figure 7;

Figure 10 is a perspective view with parts broken away depicting the portion of the pump shown in Figure 7;

Figure 11 is a view in vertical section of a pump 65 with parts broken away illustrating another form of the invention, and showing the pump piston in its lowermost position;

Figure 12 is a diagrammatic view in section and elevation of the pump shown in Figure 11 70 on a reduced scale showing the piston in its lowermost position;

Figure 13 is a view similar to Figure 12 showing the piston in an elevated position;

Figure 14 is a detail in cross section taken on the line 14—14 of Figure 11;

Figure 15 is a view in elevation taken on the line 15—15 of Figure 11;

Figure 16 is a view in vertical section as seen on the line 16—16 of Figure 11;

Figure 17 is a view in horizontal section taken on the line 17—17 of Figure 11.

Referring to the drawings more specifically, in which corresponding reference characters indicate corresponding or similar elements in the several views, A indicates a pump barrel which has a lower end wall 41 formed with an intake opening 42; the end wall 41 being here shown as comprising a plug which is threaded into the pump barrel, and from which bottom wall 41 is erected an intake tube B, the lower end of which is shown as screwed into engagement or otherwise joined with the wall or plug 41. The tube B projects upwardly into the pump barrel A and terminates in suitable spaced relation from the bottom wall 41, and has its outer periphery spaced from the inner periphery of the pump barrel in concentric relation thereto; the barrel A and tube B being cylindrical in form.

Reciprocally mounted within the pump barrel A 100 and surrounding the intake tube B is a tubular piston C carried on a pump rod D; the interior of the piston being in open communication at the lower end thereof with the interior of the pump barrel. The tube B and piston C are of 105 such lengths relative to the elected length of stroke of the piston that the lower end portion of the latter is maintained at all times during operation of the pump interposed between the tube B and the barrel A, and the piston is so 110

arranged that when in its lowermost position, its lower end will be disposed adjacent the bottom wall of the pump barrel.

Entrapped within the lower portion of the 5 pump barrel is a body of suitable protective liquid F having a density or specific gravity exceeding that of a fluid to be pumped and sufficient to float granular solids associated with such fluid, and which liquid F is insoluble in the fluid being 10 pumped. For the purpose of brevity, this liquid F will be hereinafter referred to as mercury.

The mercury body F is confined in the space between the tube B and the pump barrel A and extends on opposite sides of the lower portion of 15 the piston C to produce a mercury column G interiorly of the piston occupying a space between the lower portion of the piston and the tube B, and also to afford a mercury column H exteriorly of the piston occupying the space between the 20 lower portion of the piston and the pump barrel A.

The relative levels of the mercury columns G and H will vary during reciprocation of the piston by reason of displacement of the mercury body during movement of the piston, but the present 25 invention contemplates the provision of a means or construction whereby the relative volumes of the mercury columns G and H will be maintained substantially uniform or will be caused to assume definite relations from time to time in event of 30 any variation in their relative volumes, and whereby the levels of the mercury columns G and H will be caused to lie on substantially predetermined planes when the piston is disposed in its lowermost position.

26 A seal E is provided between the piston and the pump barrel which may be of any suitable construction.

In the form of the invention shown in Figures 1 to 10 inclusive, the upper end of the intake tube 40 B is fitted with a normally closed upwardly opening valve J, here shown as comprising a ball 43 arranged in a cage 44 carried on the upper end of the tube B, and which ball normally rests by gravity on a seat 45 whereby communication between the intake tube B and the interior of the piston C is normally closed on down stroke of the piston and when the piston is at rest, but which is open on up-stroke of the piston to admit fluid being pumped to the interior of the piston.

50 The upper end of the piston C is formed with a passage 46 which leads from the interior of the piston to the exterior thereof, and which passage is fitted with an upwardly opening valve K here shown as comprising a ball 47 which normally rests on a valve seat 48 thereby normally closing the passage 46 during up-stroke of the piston and when the piston is at rest, but which ball moves off the seat to open the passage 46 when the piston is moving on its down stroke.

60 The piston C includes a cylindrical shell 49 having a threaded tubular extension 50 on its lower end, on which is mounted the seal E here shown as comprising a series of cup leathers 51 held in place by crowding rings 52 screwed onto the threaded extension 50. The cup leathers are so arranged that on up-stroke of the piston they will effect such close contact with the walls of the pump barrel A as to effect lifting of the column of liquid in the pump casing thereabove.

65 70 The column H of the mercury extends above the cup leathers 51 a distance exceeding the length of stroke of the piston and is carried with the latter during the stroke thereof so as to maintain a body of mercury between the liquid being pumped and the piston cup leathers 51, and the

mercury column H is of such length in excess of the length of the piston stroke that such volume of mercury as may pass the cup leathers will not lower the level of said mercury column H to a point such that liquid in the pump barrel above 80 the mercury column will be lowered sufficiently to contact the portion of the pump barrel contacted at any time by the cup leathers.

The principal feature of the present invention resides in the provision of an automatically actuated valve structure in the piston for controlling the relative volumes and levels of the mercury columns G and H, and which structure, in the form of the invention shown in Figures 1 to 10, inclusive, embodies an annular valve L interposed 85 between the intake tube B and the piston shell 49 in circumferentially spaced relation thereto and mounted for vertical reciprocal movement 90 independent of the piston.

The valve L when in its uppermost position 95 abuts at its upper end against the under side of a partition M extending between the intake pipe B and the piston C and carried by the latter, and which partition is formed with ports 53 affording a communication between the spaces within the 100 piston on opposite sides of the partition and which ports are arranged to be closed by the valve L when the latter is in its uppermost position. The lower end of the valve L is tapered as indicated at 54 and is designed when the valve is in 105 its lowermost position to contact a beveled seat 55 formed on the inner periphery of the piston shell 49 to effect closure of the upper ends of a series of passages 56 leading downwardly from the seat 55 and opening exteriorly of the shell 49. 110 The valve L is thus double acting and is operable on reciprocation thereof, as will presently be described, to open and close the ports 53 and passages 56.

Extending upwardly from the upper margin of 115 the annular valve L is a pair of stems 57 which pass through a pair of diametrically opposed ports 53 and the upper ends of which stems are affixed to the lower end of a tubular sleeve 58 which encircles the intake pipe B in spaced relation thereto and the exterior of which is spaced from the interior of the piston shell 49. The sleeve 58 is formed of a metal, such as iron, which will float when sufficiently submerged in mercury; the sleeve thus serving in effect as a float to 125 maintain the valve L in its uppermost position when the mercury column D in which a portion of the sleeve is submerged is of such height within the piston as to effect flotation of the sleeve. The sleeve 58 and valve L and stems 57 are 130 formed of such weight and are arranged in such relation to the column G of mercury within the piston that when the level of the mercury is at a predetermined point when the piston is in its lowermost position, as indicated for example by 135 the line a—a in Figure 2, the valve L will be disposed in its lowermost position, and also such that when this level of the mercury is slightly increased, as indicated by the line b—b in Figure 2, the valve L will be elevated to its upper- 140 most position.

The sleeve 58 is formed with a series of openings 59 extending therethrough circumferentially thereof at a point approximating what may be termed the high level of the mercury column G 145 indicated by the line b—b in Figure 2 for the purpose of decreasing the buoyancy of the sleeve when the latter is submerged in the mercury such distance that the mercury will enter the openings 59.

In order to effect a seal between the partition M and the intake pipe B a packing 60 is carried by the partition and arranged to slidably contact the outer periphery of the intake pipe B.

5 The passages 56 open exteriorly of the shell 49 within the boundaries of a beveled seat 61 formed on the exterior of the shell and the passages 56 are normally closed at their lower ends by a sleeve valve N which encircles the shell 49 and 80 is mounted for vertical reciprocal movement thereon; the upper margin of the valve N being beveled as indicated at 62 to conform to the seat 61. The valve N is normally maintained in its seated position by reason of its being buoyant in the mercury column H but to insure rapid seating of the valve a plurality of springs 63 are arranged to bear upwardly against the lower end thereof.

As a means for facilitating assemblage of the 20 valve structure just recited the shell 49 is formed with an intermediate section O the lower end of which is screwed into engagement with the upper end of the extension 50 and the lower portion of which section is reduced in external diameter 25 to provide an annular space to accommodate the valve N and which section O is provided with the passages 56 and the valve seats 55 and 61.

The upper end portion of the section O is 30 screwed into the lower end of the shell 49 proper and has its upper end arranged to bear against the upper side of the partition M to hold the latter in position against a shoulder 65 formed interiorly of the shell.

On downstroke of the piston, the valve J is 35 closed and valve K opens to permit fluid therebeneath to flow upwardly through the passage 46 into the pump barrel above the plunger where it is entrapped and subsequently elevated and advanced to discharge by the repeated upstrokes 40 of the pump piston in the manner common to pumps of the reciprocal piston type. As the piston moves downwardly, it displaces a portion of the mercury body F, thereby causing the mercury column G to rise in the piston around the 45 tube B so that the level of the mercury column G will then be spaced above the level of the outer mercury column H; the mercury flowing past the valve L and through the ports 53 by reason of the valve L then being in its lowermost 50 position. If perchance no mercury was added to the column G on the previous upstroke of the piston the valve L will remain in its lowermost position throughout the downstroke of the piston by reason of their then being insufficient 55 mercury in the column G to float the sleeve 58, but in event of the volume of the column G being increased, which generally occurs on each upstroke of the piston, the valve L will be elevated relatively to the piston the moment that 60 sufficient mercury has flown through the ports 53 to float the sleeve 58 then closing the ports 53 and opening the upper ends of the passages 56 which condition will endure when the piston reaches its lowermost position as shown in Figures 1 and 2. The level of the column G will 65 then be slightly above normal.

In event an amount of mercury has been added to the column G on the upstroke of the piston in excess of such as will act to effect closing of the ports 53 by the valve L, such amount will be forced back into the outer mercury column H as the piston C approaches the terminus of its down stroke through the passages 56; the partition M then acting as a plunger to force the 70 excess mercury through the passages 56. The

valve N will then readily open under the pressure of mercury forced through the passages 56, and closing when this pressure terminates.

It should be noted that the displacement of the mercury of the body F and the consequent rise of the level of the column G, taking place at the end of the down stroke of the piston C, will not cause the valve L to float and assume its uppermost position closing the ports 53 in the partition M, unless an amount of mercury has leaked into column G. Consequently, any leakage into column G such as will raise the level above that ordinarily reached at the end of the downstroke of piston C may be utilized to float valve L into position closing ports 53, provided said valve will close said ports and the leakage will be returned to column H, before the levels of the columns are varied to an extent such as would expose the sand entrapped on the tops of the columns to the working surfaces of the pump piston and barrel.

When the valve L closes the ports 53, the partition M entraps the portion of column G below it and acts as a piston, exerting such pressure on the mercury thus entrapped, that 100 as the piston C nears the end of its downstroke, the mercury in an amount equivalent to the leakage from column H will be forced through ports 56 back into column H. The pressure of the mercury passing through ports 56 will open 105 the valve N. The column G in thus being approximately restored to its normal level permits valve L to gravitate to its lowermost position closing the ports 56, when the piston begins its upstroke. Since the valve L maintains its lowermost position closing ports 56 at all times except at the end of downstroke of piston C in case the leakage has occurred, it is clear that the high pressure created in column G, incident to the beginning of the downstroke of piston C 115 as necessary to open valve K, will be prevented from causing valve N to open.

The lower end of the intake pipe B may be fitted with a foot valve P, but not necessarily so; the valve being here shown as comprising a 120 ball 66 arranged in a chamber 67 in the lower end wall 41 and normally resting on a seat 68 through which the intake opening 42 passes.

The operation of the pump just described is as follows: On upstroke of the piston C, a 125 suction is induced interiorly of the latter such as to effect intake of the liquid or fluid to be pumped from intake tube B through the valve J, which body of liquid accumulates on top of the mercury column G and is confined within 130 the piston C during the upstroke of the latter. The seal E will then act to elevate the mercury column H and the column of fluid thereon previously delivered to the pump barrel to effect 135 discharge of a portion of such fluid. On upstroke of the piston, the valve L moves to its lowermost position and thereby opens the ports 53 and closes the passages 56, whereupon the level of the mercury column G will fall so that when the piston is in its uppermost position, the 140 level of the mercury column H will be above that of the mercury column G as illustrated in Figure 3. By reason of there then being a negative pressure on the mercury column G, and a head pressure on the mercury column H, a portion of the mercury from the column H may be forced downwardly past the cup leathers 51 and added to the volume of the mercury body beneath the piston. It is apparent that if the seal between 145 the piston and cylinder walls was sufficiently 150

tight, the column H of mercury above the cup leatherers would be maintained constant at all times, and there would be no passage of mercury downwardly past the cup leatherers. However, 5 this would be practically impossible to construct, as to form the cylinder or pump barrel free of small pockets can not be readily effected, and hence some slight leakage of mercury downwardly past the seal E will necessarily take place.

10 In the modification shown in Figures 11 to 17, inclusive, the seal E is disposed interiorly of the piston instead of exteriorly thereof and is arranged to coat between the walls of the intake tube B and the piston in effecting the pumping 15 action; the cup leatherers 51 being held in place on the tube B by rings 52 screwed on the latter.

A further modification is shown comprising a by-pass tube 90 located within the intake tube B having its end portions opening through the 20 walls of the tube B through ports 91 and 92; the port 91 opening to the interior of the piston above the seal E and the port 92 opening to the interior of the pump barrel below the piston and beneath the seal E, and located in the by-pass 25 90 is a downwardly opening valve 93. The valve 93 is normally maintained closed by a spring 94, although it will ordinarily float to its seated position. This valve 93 and the by-pass tube 90 serve the purpose of the valve N and passages 30 56 in the construction shown in Figure 7.

In this construction the valve L is employed only for controlling the ports 53 in the partition M; being actuated in the manner before described.

35 However, in this arrangement the mercury columns G and H are preferably on a level with each other when the piston is in its lowermost position as shown in Figure 12, at which time the valve L is floated to its port closing position, 40 and when the piston moves upwardly the level of the outer column H is lowered relatively to that of the inner column G as shown in Figure 13; otherwise the operation is similar to that described with reference to the construction 45 shown in Figures 1 to 10, inclusive; upstroke of the piston effecting intake through tube B of the liquid being pumped which liquid is delivered into the casing A above the mercury column H, and downstroke of the piston effecting displacement 50 of the liquid above the mercury column upwardly in the pump casing.

Any excess mercury as may be caused to flow from the outer column H to the inner column G past the packing E on the upstroke of the piston 55 will be directed back to the column H through the by-pass tube 90 on the succeeding downstroke of the piston thus maintaining a uniform level of the mercury interiorly and exteriorly of the piston.

60 I claim:

1. In a pump, a barrel, a piston therein, independently entrapped columns of sealing fluid in which the working surfaces of said piston and barrel are immersed, means for conveying 65 pumped fluid from beneath said columns of sealing fluid to a point thereabove, and means for maintaining said columns at predetermined levels relative to said working surfaces, including pressure creating means operative on one column to force sealing fluid into the other column.

2. In a pump, a barrel, an upstanding valved intake tube in said barrel, a tubular piston telescoping said tube, independently entrapped columns of sealing fluid disposed interiorly and exteriorly of said piston and immersing the work-

ing surfaces of said piston and barrel, and means for maintaining said columns at predetermined levels relative to said working surfaces, including means operative between the piston and said tube for creating pressure on and forcing fluid from the interior column to the exterior column.

80

3. In a pump, a barrel, a piston therein, independently entrapped columns of sealing fluid in which the working surfaces of said piston and barrel are immersed, means for conveying pumped fluid from beneath said column of sealing fluid to a point thereabove, and means for maintaining said columns at predetermined levels relative to said working surfaces, including pressure means which when leakage occurs from one column to another, operates to return said leakage.

85

4. In a pump, a barrel, a piston therein, independently entrapped columns of sealing fluid in which the working surfaces of said piston and barrel are immersed, means for conveying pumped fluid from beneath said columns of sealing fluid to a point thereabove, and means for maintaining said columns at predetermined levels relative to said working surfaces, including pressure creating means operative in one column to return leakage to the other column.

90

5. In a pump, a barrel, a piston therein, independently entrapped columns of sealing fluid in which the working surfaces of said piston and barrel are immersed, means for conveying pumped fluid from beneath said columns of sealing fluid to a point thereabove, means for maintaining said columns at predetermined levels relative to said working surfaces, and piston actuated means operating in one column to force therefrom sealing fluid which has leaked therefrom in the other column.

100

6. In a pump, a barrel, a piston therein, columns of sealing fluid in which the working surfaces of said piston and barrel are immersed, means for conveying pumped fluid from beneath said columns of sealing fluid to a point thereabove, and means for maintaining said columns at predetermined levels relative to said working surfaces, including a valved by-pass, also a means rendering said by-pass inoperative when said columns are at predetermined levels.

110

7. In a pump, a barrel, a piston therein, columns of sealing fluid in which the working surfaces of said piston and barrel are immersed, means for conveying pumped fluid from beneath said columns of sealing fluid to a point thereabove, and means for maintaining said columns at predetermined levels relative to said working surfaces, including a valved by-pass, also a means rendering said by-pass operative only after leakage of fluid from one column to another.

120

8. In a pump, a barrel, a piston therein, columns of sealing fluid in which the working surfaces of said piston and barrel are immersed, means for conveying pumped fluid from beneath said columns of sealing fluid to a point thereabove, and means for maintaining said columns at predetermined levels relative to said working surfaces, including a valved by-pass, also a pressure creating means operative in one column to force fluid through said by-pass.

130

9. In a pump, a barrel, a piston therein, columns of sealing fluid in which the working surfaces of said piston and barrel are immersed, means for conveying pumped fluid from beneath said columns of sealing fluid to a point thereabove, means for maintaining said columns at predetermined levels relative to said working surfaces.

140

150

- faces, including a valved by-pass, also a pressure creating means operative in one column to force fluid through said by-pass, and means for rendering said pressure creating means inoperative when said columns are at predetermined levels. 80
10. In a pump, a barrel, a piston therein, independently entrapped columns of sealing fluid in which the working surfaces of said piston and barrel are immersed, means for conveying pumped fluid from beneath said columns of sealing fluid to a point thereabove, means for maintaining said columns at predetermined levels relative to said working surfaces, including pressure creating means operative on one column to force sealing fluid into the other column, and means for rendering said pressure creating means inoperative when the columns are at predetermined levels. 85
- 10 11. In a pump, a barrel, an upstanding valved intake tube in said barrel, a tubular piston telescoping said tube, columns of sealing fluid disposed interiorly and exteriorly of said piston and immersing the working surfaces of said piston and barrel, and means for maintaining said columns at predetermined levels relative to said working surfaces, including a partition between said piston and said tube and having a port therethrough, a by-pass between said columns, and a float valve controlling said port and said by-pass. 90
- 15 12. In a pump, a barrel, an upstanding valved intake tube in said barrel, a tubular piston telescoping said tube, columns of sealing fluid disposed interiorly and exteriorly of said piston and immersing the working surfaces of said piston and barrel, and means for maintaining said columns at predetermined levels relative to said working surfaces, including a partition carried by said piston and surrounding and having a working fit with said tube below the level of said interior column, said partition having a port therein, and a float valve controlling said port, said tube having a valved passage therein below said partition, communicating the two columns with one another. 95
- 20 13. In a pump, a barrel, an upstanding valved intake tube in said barrel, a tubular piston telescoping said tube, independently entrapped columns of sealing fluid disposed interiorly and exteriorly of said piston immersing the working surfaces of said piston and barrel, a partition extending between said piston and said intake tube having ports therein, a normally open closure for said ports adapted and arranged to effect closing of said ports under the urge of accumulating sealing fluid interiorly of said piston, and means controlled by closing of said ports for transferring sealing fluid from the interior column to the exterior column. 100
- 25 14. In a pump, a barrel, an upstanding valved intake tube in said barrel, a tubular piston telescoping said tube, independently entrapped columns of sealing fluid extending interiorly and exteriorly of said piston, a partition extending between said intake tube and said piston and carried by the latter, said partition being formed with ports leading therethrough, means for closing said ports actuated by the sealing fluid interiorly of said piston, a passage way in said piston below said partition affording a communication between the columns of sealing fluid interiorly and exteriorly of said piston, and means actuated by the sealing fluid exteriorly of said piston for closing said passage way. 105
- 30 15. In a pump, a barrel, an upstanding valved intake tube in said barrel, a tubular piston telescoping said tube, independently entrapped columns of sealing fluid disposed interiorly and exteriorly of said piston and immersing the working surface of said piston, a passage way in the side wall of said piston for affording a communication between the columns of sealing fluid, 110 means for closing said passage way interiorly of said piston, means controlled by the accumulation of sealing fluid interiorly of said piston for operating said last named means to open said passage way adapted on down stroke of the piston to impose a pressure on the interior column of sealing fluid in excess of pressures in the exterior column of sealing fluid thereby causing transfer of a portion of the sealing fluid from the inner column to the outer column. 115
- 35 16. In a pump, a barrel having an intake opening at its lower end, a reciprocable piston in said barrel, an intake tube projecting into said piston from said opening, sealing fluid entrapped in said barrel, a seal separating said sealing fluid into two columns one of which extends around the exterior of the lower portion of said piston and the other of which extends interiorly of said piston and terminates below the upper end of said tube, a partition extending between said piston and tube, said partition being submerged in the sealing fluid within said piston, and being formed with ports, means controlled by the column of fluid within said piston for closing and opening said ports, and a normally closed passage leading from the interior of said piston below said partition to the exterior of said piston through which sealing fluid will pass from the interior column to the exterior column on down stroke of said piston when said ports are closed. 120
- 40 17. In a pump, a barrel, an upstanding valved intake tube in said barrel, a tubular piston telescoping said tube, independently entrapped columns of sealing fluid disposed interiorly and exteriorly of said piston immersing the working surfaces of said piston and barrel, a partition extending between said piston and said intake tube having ports therein, a normally open closure for said ports adapted and arranged to effect closing of said ports under the urge of accumulating sealing fluid interiorly of said piston, and means controlled by closing of said ports for 125
- 45 18. In a pump, a barrel, an upstanding valved intake tube in said barrel, a tubular piston telescoping said tube, independently entrapped columns of sealing fluid disposed interiorly and exteriorly of said piston immersing the working surfaces of said piston and barrel, a partition extending between said piston and said intake tube having ports therein, a normally open closure for said ports adapted and arranged to effect closing of said ports under the urge of accumulating sealing fluid interiorly of said piston, and means controlled by closing of said ports for 130

BENJAMIN F. SCHMIDT.
